corporation of Delaware

Application March 4, 1937, Serial No. 128,953

8 Claims. (Cl. 175—366)

This invention relates to dry disc rectifiers.

An object of the invention is to improve a rectifier of the dry disc type.

Another object is to improve the sealing means for a dry disc rectifier.

Other objects of the invention will be apparent from the following description and accompanying drawing taken in connection with the appended claims.

10 The invention comprises the features of construction, combination of elements, arrangement of parts, and methods of manufacture and operation referred to above or which will be brought out and exemplified in the disclosure hereinafter set forth, including the illustrations in the drawing.

In the drawing:

Figure 1 is a longitudinal section through a dry disc rectifier embodying features of the present invention;

Figure 2 is an end view of the rectifier with parts broken away; and

Figure 3 shows a modified form of bolt for the rectifier.

25 In its preferred form the present invention involves a novel sealing means for a dry disc rectifier whereby its performance is materially improved.

While a preferred embodiment of the invention is described herein, it is contemplated that considerable variation may be made in the method of procedure and the construction of parts without departing from the spirit of the invention. In the following description and in the 35 claims, parts will be identified by specific names for convenience, but they are intended to be as generic in their application to similar parts as the art will permit.

The present invention is particularly applicable to rectifiers of the type set forth in Samuel Ruben Patents 1,751,359, 1,751,361 and 1,751,363 issued March 18, 1930 and others. One commercial form of the rectifier comprises copper sulfide washers each having one face in contact with a magnesium washer and the opposite face in contact with a non-polarizing layer such as a washer or carbonized nickel. The washers are arranged in face to face contact in proper sequence with larger radiating fins at suitable intervals and a bolt passing through the center for clamping the groups of discs together.

Heretofore such rectifiers have been sealed externally against the effects of moisture by coating the outer edges of the washers with some sort of protecting varnish or by some other ex-

ternal sealing means and the ends of the assembly have been provided with a cork or rubber washer or gasket to prevent moisture from entering the internal space surrounding the clamping bolt. The sole purpose of such sealing has 5 been to protect the junctions from the deleterious effects of moisture.

I have now discovered that the performance of the rectifier can be materially improved by sealing both the inside and the outside edges of 10 the rectifier elements with a suitable sealing means, such as insulating varnish.

This improvement in performance extends far beyond a mere improvement in sealing against moisture. The sealing I propose appears to materially affect the electric breakdown characteristics of the rectifier.

The improvement in current rectifying capacity is remarkable. It has been found, for example, that a rectifier junction $1\frac{1}{8}$ " in diameter, 20 protected by insulating varnish on both the inner and the outer edges of the rectifier discs will safely deliver 100 amperes D. C. when connected in a 3-phase bridge rectifier. The same junction sealed in the conventional manner by cork washers at the end of the rectifier so as to adequately exclude moisture is unable, on the other hand, to deliver more than approximately 30 to 50 amperes without such serious sparking across the junction as would cause complete breakdown of 30 the rectifier in a relatively few hours of operation.

While I do not wish to be limited to any particular theory of operation it is my present opinion that the following theory might explain the 35 phenomenon: In making the copper sulfide rectifier the magnesium disc is pressed firmly against the cupric sulfide disc and an intermediate film is formed by the passage of electric current through a dielectric film previously created on 40 the magnesium by a chemical process. The electric forming process is continued until all of the magnesium area in sufficiently close contact with the cupric sulfide washer is formed into the rectifying film. Since there is a curvature at the 45 inner and outer edges of the cupric sulfide washer there is obviously an irregular line extending around both the inner and outer edges at which the cupric sulfide surface becomes tangent to the magnesium surface. Immediately adjacent the 50 outermost formed portion of the junction there will be a point at which the cupric sulfide and the magnesium are separated by an extremely small gap. Assuming this gap to be air filled, the presence of a minute hot spot in the formed 55

material at the edge of the gap or an increase in voltage across the junction due to the passage of high currents or a combination of these two causes probably results in ionization of the air in this very narrow gap, which in turn produces an arc. The destructive or erosive effect of this arc with high currents will cause the point of actual contact between discs to move inwardly and the next point of arcing would be farther 10 in from the edge of the junction. Thus the arcing will be a progressive process which will rapidly destroy the rectifying property of the entire junction.

It will be obvious that even by changing the 15 shape of the rectifier elements this borderline area of small air gap cannot be entirely eliminated.

According to the present invention, the narrow gap between the edges of the discs is filled with 20 a dielectric material which excludes air from the gap whereby no ionization can take place and there can be no arc created from this cause.

The drawing illustrates a rectifier sealed in the preferred manner of the present invention. 25 Each cupric sulfide washer 10 is in contact on one face with a magnesium washer 11 between which a suitable rectifying layer is formed by passage of an electric current as mentioned above. The other face of the copper sulfide washer 10 is 30 in contact with a non-polarizing layer 12, such as a carbonized nickel disc or one of pure-iron, or nickel plated steel, and the like. Two groups of these rectifying units are interposed between each pair of radiating plates 13 which may be 35 of any suitable metal, such as steel.

In the present instance the rectifier is intended for full wave operation and accordingly five spaced radiating plates 13 are used providing four rectifier sections. These sections can be connected in the four arms of the bridge by four 40 terminals 14, 15, 16 and 17. The rectifier plates in each section are arranged in such polarity as to provide DC across terminals 15 and 17 when AC is imposed across terminals 14 and 16.

The rectifier assembly is held together by bolt 45 18 passing through the holes in the center of the rectifier disc members. A pair of end washers 22, 24 and 23, 25 are included at each end of the assembly. Washers 22 and 23 are disposed directly on top of the end plates and are slotted to 50 permit introduction of the insulating varnish. The assembly is held under compression by spring washer 20 which is tightened against the end of the assembly by nut 19 on bolt 18.

According to the invention a sealing varnish 55 26 is coated over the internal and external edges of the rectifier washers. The varnish used should preferably have a low surface tension when applied so as to flow into the narrow spaces at the edge of the discs and completely exclude air from contact with the disc edges. Air pockets should be carefully avoided. The varnish should also preferably have a high dielectric strength. One varnish which has been found very satisfactory is made according to the following procedure: 100 60 pounds Robertson's wax, 12 gallons of raw tung oil and 5 pounds manganese resinate are cooked together at approximately 250° C. until the mixture is ready to jell and then allowed to cool. 65 While it is cooling 31 gallons of petroleum naphtha are added as rapidly as possible to complete the varnish.

The varnish may be applied to the clamped assembly before the end washers and nut are put 70 on but preferably may be introduced through the

slots or apertures 21 in the end washers. The assembly may then be baked to solidify and harden the varnish.

In Figure 3 is shown a modified form of bolt 75 27 having a hollow core 28 and a pair of radial openings 29 and 30 in the wall thereof. When this bolt is used in place of bolt 18 the slotted washers are not required as the varnish 26 may be introduced through the hollow core and radial openings. This form of bolt is particularly applicable to the larger sizes of rectifiers. 10

While the present invention, as to its objects and advantages has been described herein as carried out in specific embodiments thereof, it is not desired to be limited thereby but it is intended to cover the invention broadly within the spirit and scope of the appended claims. 15

What is claimed is:

1. A dry disc rectifier comprising a plurality of rectifier discs in face-to-face contact said discs having inner and outer edges and an insulating sealing material in solid adherent form covering all the edges of said discs so as to exclude air from the edge surfaces of said discs. 20

2. A dry disc rectifier comprising a series of rectifier discs having central apertures therein, said discs being in face-to-face contact with the central apertures of all said discs in register, and a solid adherent insulating sealing material coating the inner and outer edges of said discs. 25

3. A dry disc rectifier comprising a series of rectifier discs having central apertures therein said discs being in face-to-face contact with the central apertures of all said discs in register, and a solid adherent insulating sealing material coating the inner and outer edges of said discs so as to seal all the edge surfaces thereof. 30

4. A dry disc rectifier comprising a series of rectifier discs having central apertures therein said discs being in face-to-face contact with the central apertures of all said discs in register, and an insulating varnish coating the inner and outer edges of said discs. 40

5. A dry disc rectifier comprising a series of rectifier discs having central apertures therein and discs being in face-to-face contact with the central apertures of all said discs in register, and an insulating varnish coating the inner and outer edges of said discs so as to seal all the edge surfaces thereof. 45

6. A dry disc rectifier comprising a pair of rectifier discs having central apertures therein, said discs being in face-to-face contact with the central apertures of said discs in register, said discs thereby providing a rectifying junction between them, and a solid adherent insulating sealing material covering the inner and outer edges of the junction of said discs so as to exclude air from the edge surfaces of said junction. 55

7. A dry disc rectifier comprising a pair of rectifier discs having central apertures therein, said disc being in face-to-face contact with the central apertures of said discs in register, said discs thereby providing a rectifying junction between them, and a solid adherent insulating varnish covering the inner and outer edges of the junction of said discs so as to exclude air from the edge surfaces of said junction. 60

8. A dry plate rectifier comprising a series of rectifier plates having an aperture therethrough, said plates being in face-to-face contact and a solid adherent sealing material coating the inner and outer edges of said plates. 65
